[57] CLAIM

The ornamental design for a hand file, substantially as shown and described.

DESCRIPTION

FIG. 1 is a perspective view of the hand file showing our new design taken from the top and one side, the other side being identical thereto;

FIG. 2 is a top plan view thereof;

FIG. 3 is a bottom plan view thereof, the cutting edges being partially shown for convenience of illustration;

FIG. 4 is a front elevational view thereof; and

FIG. 5 is a rear elevational view thereof.
